COLUMBIA PLANOGRAPH CO., WASHINGTON, D.C.

UNITED STATES PATENT OFFICE.

GEORGE HENRY DUNLOP, OF AUBURN, VICTORIA, AUSTRALIA.

EXCAVATING MACHINERY.

1,098,146.

Specification of Letters Patent. Patented May 26, 1914.

Application filed July 10, 1909. Serial No. 506,967.

To all whom it may concern:

Be it known that I, GEORGE HENRY DUNLOP, a subject of the King of Great Britain and Ireland, residing at No. 20 Robinson's 5 road, Auburn, in the State of Victoria, Commonwealth of Australia, civil engineer, have invented new and useful Excavating Machinery, of which the following is a specification.

10 The present invention relates to improvements in excavating machinery and deals more particularly with an improved form of scoop.

15 The object of the present invention is to provide an improved form of scoop adapted to be used in connection with excavating machinery and comprises means for operating same.

20 The invention consists essentially in providing a movable carriage from which the scoop is adapted to be suspended, so constructed and designed that the filling, hoisting and dumping of said scoop is accomplished by means of three separate ropes 25 connected with suitable operating mechanism.

With these and other objects in view the invention consists in the construction and arrangement of parts more fully set forth 30 in the following specification, illustrated in the accompanying drawings and pointed out in the appended claim.

Referring to the drawings; Figure 1 is a side elevation of one embodiment of the 35 invention as applied to a cantaliver cable-way conveyer with the scoop shown in filling position by full lines and in dumping position by dotted lines. Fig. 2 is a sectional view over the cutting showing the side struts spaced apart with the scoop being hoisted 40 between them. Figs. 3, 4, 5 and 6 are views showing the scoop in hoisting, conveying, dumping and returning positions respectively, with part of the cable of the conveyer from which the scoop carriage is suspended. Fig. 7 is a front view of the movable carriage from which the scoop is suspended.

The invention as illustrated in Fig. 1 of 50 the drawing, is shown applied to a braced or cable-way conveyer adapted to span the ground where the scoop is to be filled and extending out over the dump in the well known manner. A track-way c^5 is built, 55 upon which the conveyer may be moved over the place of excavation. The conveyer C'

consists of struts c^2 spanning the excavation, a jib or derrick c^3 being pivotally mounted at c^4 at one end of the struts. A cable c' extends from the outer end of the derrick c^3 60 to the farther end of the side struts and serves the double purpose of the back tie for the projecting derrick and the track-way for the conveying carriage. The conveying carriage K consists of one or more 65 flanged wheels adapted to run on the cable c' . From both sides of the carriage wheels side plates P are provided, supporting a hoist pulley beneath the cable c' and around which the hoist-conveying rope passes. Suspended from the carriage K is a hook H 70 which is preferably double (one half to each side of the cable). This hook is pivotally mounted, as for example, on the axle of the upper wheel carriage K and hangs 75 down being provided with side slots h^3 in which the axle ends of an under wheel project. The lower part of the hook H is formed with two lugs h' , h^2 at the lower portion of each half of the hook. The upper 80 lug h' is adapted to sustain the loaded scoop and the lower lug h^2 to sustain the overturned scoop, as will be hereafter more fully described.

The scoop S has a cutting edge or mouth 85 at which it is filled, and a bowl for holding the material to be carried therein. Pivotally mounted to the outer sides of the scoop S is a bail or bridle B . The bail is provided near its upper portion with a transverse rod 90 b' and is suspended by the hoist-conveying rope R^3 which passes over a sheave or pulley block I , suitably carried between the carriage K and the bridle B . The hoist-conveying rope R^3 is connected to the scoop by 95 the bail or bridle (as has been described) and passes over a drum e^3 carried at the outer end of the jib or crane c^3 and from thence over a similar drum E^3 at the farther end of the strut c^2 to the winding engines. 100 By means of this rope the scoop is hoisted and carried along the cable or track-way c' . A tipping rope R^2 is attached to the scoop near the top or back and is used mainly for 105 tilting or rotating the scoop when filling and dumping. The other end of this rope passes over a winding drum E^2 to the engines. The third main-haul rope R' is attached to the scoop near the mouth and is used mainly for filling the scoop. This rope 110 passes over a winding drum E' and thence to the winding engines. A small loop b^2 is

provided on the back of the scoop and is adapted to engage with the lower lug h^2 when the scoop is in its over-turned position. The operation of the device is as follows: 5 The scoop lying in the cutting as shown in Fig. 1, is hauled forward by the main-haul and tipping ropes R' and R^2 respectively and so filled. It is then shifted by the hoist-conveying rope R^3 until the bail B strikes 10 at the hook H and rises above the upper lug h' . The hook swings back on its pivot and the scoop is lowered until the bail is borne on the upper lug h' , the transverse bar l' resting thereon (see Fig. 4). Then the carriage is hauled outward and upward over 15 the dump where the scoop is over-turned by the tipping rope R^2 , and when sufficiently over-turned for dumping, the loop l^2 on the back of the scoop strikes the hook H just 20 below the upper lug h' and forces it outward from the bail so allowing the scoop to drop until the loop rests on the lower lug h^2 , whereby the over-turned scoop is borne 25 until it has been allowed to run back preferably by gravity, or is hauled by the tipping rope until over the cutting (see Figs. 5 and 6).

I prefer to have separate engines for op-

erating the tipping and main-haul ropes and to use them in the manner more particularly described in the specification accompanying Letters Patent No. 825,200 of 1906, save that there is no backward hauling rope in this invention.

While the machine is herewith described as employed for excavating, it will be understood that it may also be used and is designed for filling and for transporting materials, as for example coal and the like.

Having described my invention what I claim is:

In excavating machinery a scoop provided with a bridle, a mainhaul rope, a tipping rope, a hoist-conveying rope, a cantaliver cableway conveyer, a carriage on said cableway, a hook suspended from said carriage and having lugs thereon, loops on the bridle and scoop to engage with said lugs—substantially as described.

In testimony whereof I have signed my name to this specification in the presence of two subscribing witnesses.

GEORGE HENRY DUNLOP.
